ATTACHMENT FOR SHOES

John C. Brown, South Weymouth, Mass.

Application May 9, 1934, Serial No. 724,780

5 Claims. (Cl. 36—7.7)

My invention relates to attachments for the soles of shoes and it has for its object to provide an improved attachment for application to the sole of a golf player's shoe and which, when in use, will afford the player better foothold than is afforded by the ordinary golf player's shoe. It is also an object of this invention to provide an attachment of the character described which will be of simple, inexpensive and efficient construction; which may be quickly applied to or removed from the sole of a shoe, and which will be adapted to be fitted to soles of different sizes.

To these ends I have provided an attachment for the sole of a shoe, said attachment having the peculiar features of construction and mode of operation set forth in the following description, the several novel features of the invention being separately pointed out and defined in the claims at the close thereof.

20 In the accompanying drawing:

Figure 1 is a bottom plan view of an attachment constructed in accordance with this invention.

Figure 2 is a section on line 2—2 of Figure 1. Figure 3 is a section on line 3—3 of Figure 1. Figure 4 is an elevation, partly broken away, of a wrench for use in connection with the attachment illustrated in Figures 1 to 4, inclusive.

The illustrated embodiment of my invention comprises two tread members indicated generally at 1 and 2, said members being fitted to and covering the bottom of the forepart of the sole of a shoe which is indicated by dotted lines at S in Fig. 3.

35 The tread member 2 comprises a solid outer marginal portion 3 formed with a longitudinal series of threaded holes 4 bordering the outer edge of said tread member while the inner portion of said tread member 2 is formed with a horizontal slot 5 extending from end to end of said member, said slot being the space between two wall-like extensions 6 and 7 of the solid outer marginal portion 3.

The tread member 1 comprises a relatively thick outer side marginal portion 8 and an inner relatively thin blade or wing portion 9 which occupies a position within the slot 5 of member 2 and which is pivotally connected adjacent to the toe end of the device to the walls 6 and 7 of member 2 by means of a pintle 10.

At its rear end the tread member 1 is made with a laterally and inwardly extending arm 11 formed along its inner side with an arcuate rack of teeth 12 which is concentric with the axis of pintle 10.

This arm 11 occupies the slot 5 and its rack of teeth 12 is engaged by a pinion 13 having trunnions 14 and 15 journaled in apertures provided in the walls 6 and 7 of tread member 2. The lowermost trunnion 15 is made with a hexagonal extension 16 adapted to receive upon it the lower end of a wrench 17, said lower end being made with a hexagonal socket 18 to fit the hexagonal portion 16 of trunnion 15.

When the wrench 17 is applied to the hexagonal portion 16 of trunnion 15 and rotated it acts through pinion 13 and rack 12 to swing the two tread members 1 and 2 relatively on pintle 10 toward or from each other.

The tread member 2 is made upon its top side 15 and adjacent to its periphery with an upstanding jaw or lug 19 to fit against the side of the shoe sole s' as indicated in Fig. 3, while the tread member 1 is made upon its top side and adjacent to its periphery with two upstanding lugs or jaws 20 and 21, one near each end of said member, for engagement with the opposite side edge of sole s' as indicated in Fig. 3.

Tread member 1 is also formed adjacent to its outer periphery with a series of tapped holes 22. 25 The tapped holes 4 and 22 of the two tread members 1 and 2 are provided for the reception of the threaded shanks 23 of spikes or carks 24 and 26. As shown in Fig. 3 the spikes of tread member 1 may be made shorter than the spikes 24 of tread member 2.

All of the spikes or carks 24 and 26 are made with hexagonal base portions 27 each of a size to fit into the socket 18 of wrench 17.

It is a feature of this invention that the spikes or carks 24 and 26 are removably mounted in the threaded holes 4 and 22 so that I may provide with each attachment a number of spikes of different lengths so that the user of the attachment can incorporate in the device spikes of the length suitable for him or spikes of different lengths, as desired. Frequently a user is best suited with spikes of one length applied to the tread member 1 and spikes of another length applied to the tread member 2, and as will be clear, the wrench 17 provides an implement by means of which the spikes may be quickly applied to or removed from the tread members. This wrench 17 is also used, as pointed out above, to operate the pinion 13, which is a matter of considerable convenience.

Between the walls 6 and 7 of tread member 2 and adjacent to the rear end thereof, is a spring 31, Fig. 1, whose free end presses yieldingly against the pinion 13 and engages the teeth there-

of to prevent rotation of the pinion in one direction. Detent 31 is constructed with a lateral projection 32 occupying a slot formed in the bottom wall 7 and by means of this projection the detent 5 can be manually disengaged from the pinion without removing the device from the shoe.

In applying the attachment to the sole of a shoe it is placed in position against the forepart 10 of said sole while the two tread members 1 and 2 occupy more or less separated relationship. Then by means of the wrench 17 applied to the 15 hexagonal portion 16 of the trunnion of pinion 13 the latter is rotated in a direction to forcibly swing the two tread members together so that their lugs 19, 20 and 21 are forced against the 20 opposite edges of the sole s'. When the attachment is thus adjusted so as to firmly grip the sole the spring detent serves to lock the parts in their sole-gripping positions.

What I claim is:

1. An attachment of the character described for application to the forepart of the sole of a shoe, said attachment comprising a pair of tread members having their forward ends pivotally connected, one of said members being disposed at one side of said forepart and made with an arcuate rack of teeth concentric with said pivotal connection and the other of said members being disposed upon the opposite side of said forepart, and a member-operating element rotatably mounted on said last-mentioned member and meshing with said rack of teeth, said element being operable when rotated in one direction to swing said two members relatively toward each other thereby to fixedly clamp the attachment to the opposite side edges of said forepart and when rotated in the opposite direction to swing said two members away from each other.

2. An attachment of the character described for application to the forepart of the sole of a shoe, said attachment comprising a pair of tread members having their forward ends pivotally connected, one of said members being disposed at one side of said forepart and made with an arcuate rack of teeth concentric with said pivotal connection and the other of said members being disposed upon the opposite side of said forepart, and a toothed member-operating element rotatably mounted on said last-mentioned member and meshing with said rack of teeth, said element being operable when rotated in one direction to swing said two members relatively toward each other thereby to fixedly clamp the attachment to the opposite side edges of said forepart and when rotated in the opposite direction to swing said two members away from each other.

3. An attachment of the character described for application to the forepart of the sole of a shoe, said attachment comprising a pair of tread members each provided upon its top side and at its outer edge with a sole-engaging lug and upon its bottom side with a plurality of spikes, one of

said members being disposed at one side of said forepart and made adjacent to its rear end with an arcuate rack of teeth and the other of said members being disposed upon the opposite side of said forepart; means pivotally connecting said members adjacent to their forward ends and with respect to which said arcuate rack of teeth is concentric, and a pinion rotatably mounted on said last-mentioned member and meshing with said rack of teeth, said pinion being constructed with a trunnion having an extension projecting below the bottom of said last-mentioned member which extension is non-circular in cross section thereby to adapt it for engagement with a wrench by which said pinion is rotated in one direction to swing said two members relatively toward each other thereby to fixedly clamp the attachment to the opposite sides edges of said forepart and by which said pinion is rotated in the opposite direction to swing said two members away from each other.

4. An attachment of the character described constructed in accordance with claim 3 wherein one of said tread members is made with a horizontal slot within which said pinion is mounted, and wherein the other of said members is made with a relatively thin blade occupying said slot and on which said arcuate rack of teeth is provided.

5. An attachment of the character described for application to the forepart of the sole of a shoe, said attachment comprising a pair of tread members each provided upon its top side and at its outer edge with a sole-engaging lug and upon its bottom side with a plurality of spikes, one of said members being disposed at one side of said forepart and made adjacent to its rear end with an arcuate rack of teeth and the other of said members being disposed upon the opposite side of said forepart and formed with a horizontal slot into which said first-mentioned member extends; means pivotally connecting said members adjacent to their forward ends and with respect to which said arcuate rack of teeth is concentric; a pinion rotatably mounted on said last-mentioned member within said slot and meshing with said rack of teeth, said pinion being constructed with a trunnion having an extension projecting below the bottom of said last-mentioned member which extension is non-circular in cross section thereby to adapt it for engagement with a wrench by which said pinion is rotated in one direction to swing said two members relatively toward each other thereby to fixedly clamp the attachment to the opposite side edges of said forepart and by which said pinion is rotated in the opposite direction to swing said two members away from each other, and means adjustably mounted on said last-mentioned tread member and engaging said pinion to lock the latter in its adjusted position.

JOHN C. BROWN.
